(57) **CLAIM**

The ornamental design for a filament tape utilization device, as shown and described.

DESCRIPTION

FIG. 1 is a top left side perspective view of the subject device; FIG. 2 is a bottom right side perspective view of the subject device;

FIG. 3 is a bottom plan view of the subject device;

FIG. 4 is a top plan view of the subject device;

FIG. 5 is a left side elevation view of the subject device;

FIG. 6 is a right side elevation view of the subject device;

FIG. 7 is a front elevation view of the subject device; and,

FIG. 8 is a rear elevation view of the subject device.

The broken line showing of the recessed area is for the purpose of illustrating portions of the subject device and forms no part of the claimed design.

1 Claim, 4 Drawing Sheets

FIG. 3

FIG. 4
